A. N. OTIS

SINGEING APPARATUS

Filed Oct. 2, 1926

Inventor:
Albert N. Otis,
by *Alexander S. Gandy*
His Attorney

UNITED STATES PATENT OFFICE.

ALBERT N. OTIS, OF SCHENECTADY, NEW YORK, ASSIGNOR TO GENERAL ELECTRIC COMPANY, A CORPORATION OF NEW YORK.

SINGEING APPARATUS.

Application filed October 2, 1926. Serial No. 139,202.

My invention relates to singeing apparatus used in singeing textile materials, and has for its object the provision of simple, reliable and efficient electrically heated singeing apparatus.

More particularly my invention relates to singeing apparatus employing an electrically heated bar as the singeing element, the woven fabric being passed over the bar so as to be singed. In one of its aspects my invention relates to the provision of a singeing bar heated by passing an electric current through it which is sufficiently rigid to withstand the pressure of the cloth without flexure, which will not warp, and in which the heat is generated near the singeing surface where it is immediately available.

For a more complete understanding of my invention reference should be had to the accompanying drawing in which Fig. 1 is a plan view of electric singeing apparatus embodying my invention; Fig. 2 is a diagrammatic view showing the use of the apparatus in singeing cloth; Fig. 3 is a fragmentary view partially in section showing details of construction; Fig. 4 is a sectional view along the line 4—4 of Fig. 1 looking in the direction of the arrows; while Figs. 5, 6 and 7 are views showing details of construction; Fig. 7 being a sectional view along the line 7—7 of Fig. 6.

Referring to the drawing, in one form of my invention the metallic singeing bar 10 is mounted on a series of blocks 11, 12 and 13 made of suitable refractory, electrically insulating material, such as fire clay. These blocks are secured in end-to-end relation between two metallic side bars 14 and 15, shown as channel irons, the blocks being clamped between the channel irons by means of suitable bolts 16. The bar 10 extends lengthwise of this support formed by the insulating blocks, and it is secured at frequent intervals along its length to the supporting blocks by means of anchors 17. These anchors are metallic strips which are welded or otherwise secured to the inner side of the singeing bar and extend at right angles to the singeing bar, the inner ends of the anchors being bent over at right angles to form projections 18 extending alternately in opposite directions and at right angles to the length of the singeing bar. As shown in Fig. 4 the anchor members 17 may be formed of U shaped strips, one side of each strip being welded to the inner side of the singeing bar.

The blocks of insulating material 11, 12 and 13 forming supports are each made in two pieces which are clamped together between the supports 14 and 15. The block 11 for example comprises the two pieces 11^a and 11^b (Fig. 4). As shown in Figs. 3 and 4 the adjoining surfaces of the two pieces are cut away at 19, adjacent the other end, to provide a space for the shanks of the anchors, that is, the portions of the anchors extending at right angles to the singeing bar. The two parts are further each provided with a groove 20 extending parallel with its length and in position to receive the laterally bent ends 18 of the anchors. In assembling the singeing bar and insulators the insulators are placed over the anchors and then clamped together between the supports 14 and 15 whereby the singeing bar is secured thereto. This support for the singeing bar holds it securely throughout its entire length so that it is impossible for the bar to become distorted by changes in temperature. It is highly essential that the bar be absolutely straight at all times in order to provide for uniform singeing of the goods.

Preferably also the singeing bar is provided with a longitudinal central ridge coming to a blunt point or edge. As shown in Figs. 6 and 7, the bar consists of a strip of metal having a rectangular cross section and having its sides bent over from the center very slightly so as to have an open V cross section, the bar being arranged on the support so that the ridge or edge 21 is on the outer side on the singeing surface. The object of so shaping the singeing bar is to provide for contact between the cloth and substantially the entire width of the bar in spite of any irregularity in its position. It will be observed that with this shape the bar may be tipped forward or backward somewhat, that is, moved about an axis parallel with its length without materially changing the width of the contact surface with the cloth, whereas if a flattened singeing surface were used a slight tipping displacement of the bar with relation to the plane of the cloth would result in edge contact only.

A short flat section is provided at each end of the bar to provide for the connection of electrical terminals. These terminals consist of substantially rectangular metallic members 22, shown in Fig. 5, which have their ends connected to the inner side of the singeing bar at the ends thereof. A rectan-

gular metal plate 23 is also secured in the angle at the junction between the terminal 22 and the bar so as to form a bracket and provide for a more rigid joint. This plate 5 also affords an additional path for the electric current whereby the conductivity at the point is increased, and as a result the heating of the terminals decreased. As shown in Fig. 3, the plate 23 extends into the recess between the insulating blocks, whereby warping 10 is prevented. Preferably the connections between the parts 22 and 23 and the bar are made by welding, a metallic plate being placed on the bar at each end to provide additional stock whereby the welding operation 15 is facilitated and the electrical conductivity further increased.

A low voltage electric current sufficient to heat the bar to the desired singeing temperature is supplied by means of a transformer 24, the low voltage secondary terminals of 20 which are connected to the terminals 22. As shown the transformer comprises an elongated, rectangular magnet iron core 25. The secondary winding of the transformer, as 25 shown, consists of a pair of heavy copper conductors to facilitate bending, these conductors being placed side by side to form a secondary conductor 26 of high current capacity. This secondary conductor extends 30 through the core and may make one or more turns on the core to give the required voltage. As shown, two turns are provided. A primary winding 27 is also mounted on the 35 core. It will be observed that the singeing bar and its insulating support together with the transformer 24 form a compact unitary device.

In using the singeing device, it is supported in a suitable framework cooperating 40 with the supporting clamps 14 and 15. As shown, lateral lugs 28 are provided on the clamps 14 and 15 so that the device may be supported between two parallel members of 45 a framework which are embraced by the lugs 28.

A typical installation of singeing devices in a complete singeing apparatus is shown 50 diagrammatically in Fig. 2. The singeing devices are mounted in two groups 29 and 30 of three devices each, the devices in each group being spaced vertically one above the other. The cloth 31 to be singed is passed over suitable rollers on a movable framework 32 so as to pass through the framework in two vertical lengths 33 and 34. The framework 32 may be moved forward toward the right as shown in the drawing until these vertical lengths of cloth engage the heated surfaces of the singeing bars, and when desired the framework may be moved backward toward the left out of engagement with the bars. This arrangement provides 55 for the heating of the bars prior to engagement with the cloth. In other words while

the bars are being heated the framework will be moved to the left, and after the bars have been brought up to the desired singeing temperature the framework will be moved toward the right to bring the cloth into engagement with the bars and the cloth fed through the singeing apparatus. It will be observed that the two groups 29 and 30 of the singeing devices are arranged to singe opposite sides of the cloth. 75

Preferably cooling means is provided for the terminals 22. As shown in Fig. 5 the blocks are each provided with a duct 35 through which cooling water is circulated.

It will be observed that the singeing bar 80 10 is relatively thin as compared with its width whereby the cross section is reduced so that sufficient resistance is obtained to give the desired heating effect. Furthermore this shape of the bar provides for the generation 85 of the heat near the singeing surface. The bar is further arranged so that it is held very rigidly to withstand the pressure of the cloth against it and to prevent warping. It will be observed that the anchor members 17 are 90 free to slide laterally in the recesses in the supporting insulators in accordance with the longitudinal expansion and contraction of the bar 10. The bar is thus rigidly supported but at the same time it is free to expand and 95 contract.

While I have described my invention as embodied in concrete form and as operating in a specific manner in accordance with the provisions of the patent statutes, it should be 100 understood that I do not limit my invention thereto since various modifications thereof will suggest themselves to those skilled in the art without departing from the spirit of my invention the scope of which is set forth 105 in the annexed claims.

What I claim as new and desire to secure by Letters Patent of the United States, is,—

1. A singeing element for cloth singeing machines comprising a bar provided with a central longitudinal ridge on one side forming a singeing surface, an insulating support for said bar, and means for slidably securing said bar at intervals to said support so that said bar may move lengthwise of said support. 110

2. A singeing element for cloth singeing machines comprising an elongated electrically insulating support, a bar extending lengthwise of said support, means for slidably securing said bar to said support at intervals whereby said bar and support may have relative longitudinal movement, and means for passing an electric heating current through said bar. 115

3. A singeing element for cloth singeing machines comprising an electrically insulating support, an electrically conducting bar extending lengthwise of said support, recesses in said support, anchor members se- 120 125 130

cured at intervals to said bar interlocking with said support in said recesses, and means for passing an electric heating current through said bar.

- 5 4. A singeing element for cloth singeing machines comprising a bar, an electrically insulating support for said bar provided with a longitudinal recess, and holding members secured at intervals to the inner side of said bar and extending into said recess into interlocking engagement with said support, said holding members being free to slide in said recess in accordance with longitudinal expansion and contraction of said bar.
- 10 5. An electrically heated singeing element comprising a bar, a support for said bar extending lengthwise thereof comprising a pair of electrically insulating members provided with registering recesses, holding members secured at intervals to the inner side of said
- 15
- 20

bar and extending into said recesses into interlocking engagement with said holding members so as to hold said bar in lengthwise engagement with said support, a primary winding, a magnet core therefor, and a conducting bar interlinking with said core having its ends connected to the ends of said bar. 25

6. A singeing element for cloth singeing machines comprising a bar inclined from the center on one side to form a singeing surface, 30 an elongated electrically insulating support extending lengthwise of said bar in engagement therewith, said support being provided with recesses and anchor members secured to said bar at intervals and cooperating with 35 said recesses for holding said bar to said support.

In witness whereof, I have hereunto set my hand this 1st day of October, 1926.

ALBERT N. OTIS.
